The ornamental design for a vortex water flow accelerator, as shown and described.

DESCRIPTION

FIG. 1 is a perspective view of a vortex water flow accelerator showing my new design;

FIG. 2 is another perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof; and,

FIG. 8 is a schematic diagram of the vortex water flow accelerator in a position of use.

The broken lines in the figures are for the purposes of illustrating portions of the vortex water flow accelerator, which form no part of the claimed design.
